CLAIM

The ornamental design for a note dispenser, as shown and described.

DESCRIPTION

FIG. 1 is a perspective view of the new design for a note dispenser;

FIG. 2 is a front view thereof, the rear view being a mirror image thereof;

FIG. 3 is a top view thereof;

FIG. 4 is a bottom view thereof; and,

FIG. 5 is a perspective view thereof showing the note dispenser with a note.

The broken lines in FIG. 5 are included for the purpose of showing portions that form no part of the claimed design.

1 Claim, 2 Drawing Sheets(56)
